RECEPTACLE CLOSURE

Augustus L. Merolle, Brooklyn, N. Y., assignor to
 Empire Metal Cap Co., Inc., Brooklyn, N. Y., a
 corporation of New York

Application December 24, 1931, Serial No. 582,913

6 Claims. (Cl. 215—43)

This invention relates to a receptacle closure, and particularly to a closure which is formed of two cup-shaped pieces of sheet material nested together one within the other, the inner member or shell being formed with means for engaging a receptacle to hold the closure connected with the receptacle, and the outer member or cap constituting an ornamental cover, protector and reinforcement for the inner member, and an object 5 of the invention is to provide a receptacle closure of this character which shall be easy to manufacture, which will be of ornamental and attractive appearance, which will be strong and substantial, and which may be produced in quantities at 10 small cost.

A further object is to provide a receptacle closure of this character in which no raw edge of material will be exposed at any point throughout the closure either inside or outside thereof.

20 A further and more detailed object is to provide simple and efficient means, effective without the performance of an additional operation during manufacture, of retaining the inner and outer members against possibility or rotation with respect to each other at all times.

25 A further detailed object is to so construct the two members of the closure that they will have a constant resilient pressure against each other effective to hold them against possibility of relative movement during use.

30 Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claims.

In the accompanying drawing which is to be 40 taken as a part of this specification, and in which I have shown merely a preferred form of embodiment of the invention:—

Fig. 1 is a side elevational view of a receptacle closure constructed in accordance with this invention, a part being broken away and shown in vertical section for the better illustration of details.

Fig. 2 is a fragmentary top plan view of the structure seen in Fig. 1.

Fig. 3 is a fragmentary detail sectional view upon the plane of line III—III of Fig. 1, and;

Fig. 4 and 5 are diagrammatic sectional views illustrating slightly modified forms of the cap and shell members and their co-operative features.

Fig. 6 is a sectional view similar to Fig. 4, on an enlarged scale, but broken away to show one side only, the other side being identical;

Fig. 7 is a section on the line 7—7 of Fig. 6, and to the same scale, but broken away;

Fig. 8 is a sectional view similar to Fig. 5, on an enlarged scale, but broken away so as to only show one side, the other side being identical; and;

Fig. 9 is a section on the line 9—9 of Fig. 8, but 10 partly broken away.

Referring to the drawing for describing in detail the structure therein illustrated, and referring first to the structure illustrated in Figs. 1 to 3, the reference character L indicates the 15 inner member of the receptacle closure while the reference character G indicates the outer member of the closure.

The inner or cap member L is made of thin sheet material, such as sheet metal, and is formed 20 with a top wall 1 for overlying the receptacle opening and a marginal annular side wall or flange portion 2 for overhanging the annular surface of the mouth of the receptacle in the usual manner. The side wall 2 is suitably shaped, 25 as for instance by having threads as 3 pressed therein, to releasably engage co-operative formations provided upon the outer annular surface of the receptacle.

At the lower margin of the side wall 2 said wall 30 is flared outwardly as at 4 and thence extended downwardly and inwardly as at 5.

The outer or shell member G is made of thin sheet material, such as sheet metal, and is formed 35 with a top wall 6 for overlying the top wall 1 of the cap and a marginal annular side wall or flange portion 7 for overhanging the side wall 2 of the cap member.

At the lower margin of the side wall 7 said wall is turned inwardly as at 8 to underlie the in-turned portion 5 of the cap member, and is thence turned upwardly and outwardly as at 9, and thence again downwardly as at 10 within the lower margin of the cap member.

The lower marginal portions of the side walls 45 of the shell and cap members are thus inter-folded with each other into an inwardly disposed wire edge, which is designated generally by the reference character H, which is of double thickness throughout an appreciable portion of its 50 cross sectional circumference, thereby producing a wire edge of great strength and stiffness.

It is noted that no raw edge of metal is at any point in this closure exposed to vision or to access of a corroding substance, such for instance as 55

ketchup, from within the receptacle. The raw edges, as 12 and 11, of the shell and cap members are curled within the wire edge H where they are both permanently confined wholly out 5 of sight and not accessible to any corroding influence at least in-so-far as such influence might result detrimentally to the appearance of the closure.

In forming the wire edge H the lower marginal 10 portion of the shell member is curled about the lower marginal portion of the cap member so that both these lower portions are simultaneously curled into interfolded relation as the operation of completing the wire edge proceeds.

15 It is important further to note that during this operation of curling together into interfolded relation the lower margins of the cap and shell, a powerful pressure is necessarily exerted between the two members tending to force the cap 20 member relatively upwardly and the shell member relatively downwardly, thereby pressing the top wall members 1 and 6, respectively of the cap and shell members tightly against each other. The effect of this force is made more pronounced by reason of the fact that the wire edge is of considerable cross sectional width radially 25 of the closure, thereby bringing a generous expanse of the two members of the closure against each other at the wire edge and in the direction 30 of the pressure.

It is further to be noted that in forming the outturned portion 9 of the wire edge, said portion is forced snugly against the relatively under-surface of the outflaring portion 4 of the 35 cap member, thereby adding further pressure of the cap member relatively upwardly against the top wall of the shell member.

The outflaring portion 4 of the cap member, against which all of the pressure from the wire 40 edge is exerted, is so formed as to possess an appreciable degree of resilience. Its outflaring disposition is such that it constitutes in effect an annular resiliently flexible connection between the wire edge portion and the remainder of the cap member, and the pressure from the parts of the wire edge is exerted substantially at the outer circumferential margin of this resilient connection.

The pressure from the wire edge exerted for 50 holding the two top walls 1 and 6 against each other is transmitted through the flexible resilient portion 4 of the cap member and is intended to be sufficiently great so as to cause a certain amount of flexing of said portion 4 and 55 thereby generate a perpetually maintained resilient pressure of the top walls of the cap and shell members against each other.

The interfolded relationship of the lower margin of the cap and shell members, in the wire 60 edge, are in most cases sufficient to prevent any possibility of inter-rotation of the shell and cap members in use, but the present invention contemplates that, if desired, further means to this end may be provided as for instance by forming 65 co-operative interengaging conformations upon the cap and shell members such that when said members are held together in position as hereinabove set forth, said co-operative conformations will be held in such relation to each other 70 as to positively lock the cap and shell members against even the remotest possibility of rotary movement with respect to each other.

An example of such a means is illustrated herein as consisting of corrugations as 13 formed 75 upon the top wall 1 of the cap member and

similar corrugations as 14 formed upon the top wall 6 of the shell member, the corrugations 13 and 14 being set to radiate from the center of the walls 1 and 6 and being disposed so that they mesh together, as most clearly indicated 5 in Fig. 3.

The corrugated surfaces above referred to may be formed in the walls 1 and 6 prior to assembling the cap and shell members together, and when said members are placed together the corrugations will naturally co-incide and intermesh so that thereafter, when the wire edge has been completed, they will be so held in intermeshing relation as indicated in Fig. 3 that no possibility of relative rotary movement of the cap and shell members is present.

If desired the material, for instance sheet metal, from which the cap and shell members are formed may be lacquered upon both of its surfaces, and when this is done the contact surfaces of the two members, not only in the corrugations 13 and 14, but also at the wire edge H, will be held cemented together, by the lacquer, and thus the members are additionally retained against relative movement. The presence of the lacquer will also serve to seal the joint between the portion 9 of the wire edge H and the portion 4 of the cap member more effectually against the possibility of movement of moisture or other substance into or out of the interior of the wire 30 edge.

In addition to the wire edge itself constituting a stiff re-inforcing band at the lower margin of the closure, the outflaring portion 4 of the cap member adds greatly to the strength of the 35 wire edge in always maintaining the true circular contour of the lower portion of the closure.

In instances where the closure is intended to be threaded onto a receptacle, as in the case of 40 the closure herein illustrated, the wire edge H is positioned so that although turned inwardly of the closure, its innermost diameter is equal to or greater than the outer-most diameter of the threads on the receptacle, thereby to clear 45 said threads when the closure is being applied onto or removed from the receptacle, as will be readily understood. In the closure as illustrated the wire edge stands radially outside of the vertical plane of the inner surface of the largest 50 diameter of the threads 3 of the cap member.

In the modification illustrated by Figures 4 and 6 the structure is the same as has already been set forth except that in this instance the lower annular portion of the cap member is 55 not curled inwardly within the wire edge as in the previous views, but extends straight downwardly from the portion 4, as at 15, within the wire edge. The extreme lower edge of the cap member may have contact with the interior surface of the wire edge but it is intended that the main force from the wire edge against the cap member, for holding the top walls 6 and 1 of said members pressed together, is exerted against the cap member by the inner edge portion as 65 16 of the wire edge where it engages against the portion 4 of the cap member as indicated.

This view also shows the outer annular wall 1 of the shell member as fitting more snugly about the wall 2 of the cap member. In fact it 70 is intended that the inner surface of the wall 1 shall engage against, or be engaged by, the outer surface of the wall 2 so that said walls mutually reinforce each other substantially throughout their extent, thereby enabling the 75

use of a grade or kind of sheet material relatively thinner and weaker and cheaper, than the grade required in the building up of a structure as hereinabove described, and without loss of strength in the completed closure.

The lower marginal part of the wall 7 of the shell member is shaped so as to flare outwardly as at 17 above the outer annular portion of the resilient part 4 of the cap member. In practice it is intended that when the shell and cap members are originally nested together, the part 4 shall be spaced slightly away from the part 17, but that in the operation of forming the wire edge H the edge portion 16 of the said wire edge 15 will engage against the portion 4 and flex said portion 4 toward and preferably against the inner surface of the portion 17 thereby forming a lock between the cap and shell members.

Also concerning the structure of Fig. 4 it is 20 further noted that the inter-engaging relationship of the cap and shell members at the wire edge is such that, even if the upper portions of these two members, for instance the top walls 1 and 6, have no engagement with each other, 25 still the two members would be efficiently locked together. The portion 17 of the shell member provides a shoulder or downwardly facing surface portion of the shell member against which the upwardly exerted pressure from the edge 30 portion 16 of the wire edge H clamps and grips the portion 4 of the cap member. In some instances it may be desirable to construct a closure in this manner, the portions as 13 and 14 being provided, if found necessary, merely as additional 35 means for retaining the cap and shell members against inter-rotation, but there being no appreciable pressure of said corrugated portions against each other vertically of the closure.

In the modification illustrated by Fig. 5 the 40 structure is again the same as described with respect to the previous figures except that in this instance the lower annular portion of the cap member does not extend downwardly at all from the resilient flaring portion 4. The portion 4 45 simply projects radially outwardly and terminates with its raw edge surface facing directly radially outwardly of the closure. In this instance the wire edge H simply curls inwardly beneath the outer margin of the portion 4 and 50 is intended to press tightly thereagainst, preferably so as to flex said portion 4, to the same extent as heretofore. In this illustration the outer wall as 7 of the cap member is shown as varying slightly from the forms in the previous 55 figures, in that it is of a generally frusto-conical shape, being of a diameter at its lower portion sufficient to just receive the outflaring flange 4 of the cap, and being of a diameter at its upper portion to just receive the upper portion of the 60 cap. Since the cap L is formed with no extension beyond the portion 4 it requires somewhat less material than in either of the other illustrated structures.

By making the wall 7 of the shell member 65 of frusto-conical shape said wall is materially stiffened not only in the finished closure but also against collapse during the operation of turning in the wire edge H.

If desired the wall 7 of the shell member of 70 the structures, as illustrated in Figs. 1 and 5, may be formed with vertically extending corrugations, being indicated by the reference character 18 in Fig. 5, and the innermost portions of these corrugations may, if desired, be disposed so as 75 to rest against the outermost portions of the

wall 2 for mutual re-inforcement of the walls 2 and 7 as above referred to concerning the illustration Fig. 4. In the structure illustrated by Figs. 1 and 5 these corrugations 18 may, if desired, be so formed that their lower end portions 5 will constitute a series of downwardly facing shoulders, as 19, corresponding to the downwardly facing shoulder formed by the portion 17 of Fig. 4, and this shoulder, or shoulders, 19 may be disposed to stand so as to be engaged by the 10 margin of the portion 4 of the cap when the wire edge presses against the said portion 4 as described with reference to the parts 16 and 17 of Fig. 4.

During the operation of rolling in the wire 15 edge H against the margin of the portion 4, said margin may, if desired, be pressed sufficiently tightly against the series of shoulders as 19 to cause each of the shoulders in said series to produce an indentation of greater or less depth in 20 the margin of the portion 4, and, since the wire edge will continue to hold the indented margin of the portion 4 against the shoulders, the shell will be thereby positively locked against rotation 25 with respect to the cap.

The presence of the corrugations 18 in the wall 7 provides an additional advantage in that it furnishes a means by which the closure may be more efficiently gripped in a machine for performing the operation of attaching the closure 30 onto a receptacle. The shoulder, or shoulders 19, like the shoulder 17, forms a stop above or behind the margin of the portion 4 which is very desirable in preventing distortion of any of the parts during the operation of rolling in 35 the wire edge.

It is noted that in both the structures of Figs. 4 and 6 and 5 and 8 the raw edges of the material of the cap and shell members are concealed and protected to the same purpose as above referred 40 to concerning the structure Figs. 1 to 3.

As many changes could be made in this construction without departing from the scope of the invention as defined in the following claims, it is intended that all matter contained in the 45 above description, or shown in the accompanying drawing, shall be interpreted as illustrative only and not in a limiting sense.

Having thus described my invention, what I 50 claim as new and desire to secure by Letters Patent is:—

1. A receptacle closure consisting of a cap member and a shell member, the shell member having a top wall portion and a marginal depending side wall, the cap member having also a 55 top wall portion and a marginal depending side wall and being nested within the shell member so that the top wall portions of said two members stand adjacent each other, the side wall portion of the shell member being formed with vertically 60 disposed corrugations circumferentially thereof disposed to project inwardly of the shell member so as to engage the side wall portion of the cap member for mutual re-inforcement of said two side wall portions, said corrugations providing a series of downwardly facing shoulders upon the inner surface of the shell member, the side wall portion of the cap member having a shoulder forming part to engage the mentioned series of shoulders, and means formed upon the 65 side wall portion of the shell member engaging the shoulder forming part of the side wall portion of the cap member to hold said shoulder forming part of the cap member against said series of shoulders.

2. A receptacle closure consisting of a cap member and a shell member, the shell member having a top wall portion and a marginal depending side wall, the cap member having also a top wall portion and a marginal depending side wall and being nested within the shell member so that the top wall portions of said two members stand adjacent each other, the side wall portion of the shell member being formed with a series of circumferentially spaced shoulders interiorly thereof, the side wall portion of the cap member having a shoulder forming part disposed to engage the mentioned series of shoulders, and the side wall portion of the shell member being bent to form an inturned wire edge thereon, a portion of which is disposed to constitute another shoulder interiorly of the closure in such a position as to press against the shoulder forming part of the cap member and press said shoulder forming part of the cap member against said series of shoulders.
3. A receptacle closure consisting of a cap member and a shell member, the shell member having a top wall portion and a marginal depending side wall, the cap member having also a top wall portion and a marginal depending side wall and being nested within the shell member so that the top wall portions of said two members stand adjacent each other, the top wall portions of each of said two members being formed with corrugations which mate together and thereby cooperate when said cap member is placed tightly in its nesting position against the mentioned top wall portion of the shell member to hold said cap and shell members against rotation with respect to each other, and said cap and shell members having other portions interengaging to press and hold said cap member tightly in its nesting direction against the mentioned top wall portion of the shell member to thereby render said first cooperative portions effective.
4. A receptacle closure comprising a cap member and a shell member, the shell member having
- a top wall portion and a marginal depending side wall, the cap member having also a top wall portion and a marginal depending side wall and being nested within the shell member so that the top wall portions of said two members stand adjacent to each other, said top wall portions of the cap and shell having interengaging corrugations and said cap and shell engaging with each other below said top walls to hold said members in nested relationship and said corrugations in engagement.
5. A receptacle closure comprising a cap member and a shell member, the shell member having a top wall portion and a marginal depending side wall, the cap member having also a top wall portion and a marginal depending side wall and being nested within the shell member so that the top wall portions of said two members stand adjacent each other, the side wall portion of the shell member being formed with vertical corrugations circumferentially thereof, disposed to project inwardly of the shell member, the side walls of said cap and shell members engaging at the bottom marginal portion of the cap side wall, and said corrugations in the side wall of said shell being located above the said engaging portions of the side walls of the cap and shell and between them and the top walls of the cap and shell, said top wall portions of the cap and shell having interengaging corrugations.
6. In a closure cap of the class described, the combination of an inner cap member having a skirt portion provided with container engaging means, and an outer shell member adapted to encase said cap member, said shell member having a depending skirt provided with an inturned rolled edge turned into substantially a hollow bead having a convex upper outer surface on the interior of said shell member, said upper convex surface of said bead engaging the bottom of the skirt of said cap member to secure said cap and shell members together.

AUGUSTUS L. MEROLLE.
